United States Patent Office

Des. 173,697
Patented Dec. 21, 1954

173,697

DESK

Arnold Friedmann, New York, N. Y., assignor to Jesse Silberstein and Nancy Silberstein, New York, N. Y.

Application June 10, 1954, Serial No. 30,916

Term of patent 7 years

(Cl. D33—7)

Fig. 1.

Fig. 2.

To all whom it may concern:

Be it known, that I, Arnold Friedmann, a citizen of Israel, residing in the county of Queens, city and State of New York, have invented a new, original, and ornamental Design for a Desk, of which the following is a specification, reference being had to the accompanying drawing, forming a part hereof, in which:

Fig. 1 is a perspective view of the front of a desk embodying my new design.

Fig. 2 is a perspective view of the rear of the desk.

I claim:

The ornamental design for a desk, as shown.
